UNITED STATES PATENT OFFICE

JOHN J. COMPO, OF DEFIANCE, OHIO

MUFFLER

Application filed December 21, 1929. Serial No. 415,655.

My invention has for its object to provide an exceedingly efficient muffler for muffling the sound produced by the exhaust of internal combustion engines. The invention is particularly adapted for use in connection with motor vehicles, and provides means for readily connecting the muffler in exhaust pipes of different sizes, and for directing exhaust gases through a series of expansion chambers which progressively reduces the pulsating pressure to finally a substantially constant pressure, whereby the extreme pulsatory movement of the gases that enter the muffler are reduced to a substantially constant current or flow of the gases at the outlet of the muffler.

The invention may be contained in mufflers that vary in their details of construction and, to illustrate a practical application of the invention, I have selected a muffler containing the invention, and shall describe it hereinafter. The particular structure selected is shown in the accompanying drawing.

Fig. 1 is a longitudinal section of the particular muffler selected for purposes of illustration. Fig. 2 is a view of a section taken on the plane of the line 2—2 indicated in Fig. 1. Fig. 3 is a view of a section taken on the plane of the line 3—3 indicated in Fig. 1. Fig. 4 is a view of a section taken on the plane of the line 4—4 indicated in Fig. 1. Fig. 5 is a view of a longitudinal section of the connector for connecting one of the ports of the muffler with exhaust pipes of different sizes.

The muffler illustrated in the drawing comprises a drum, or shell, 1 cylindrical in form, and a core 2 formed of a pair of interconnected cones 3 and 4, which form within the shell 1, chambers that enable repeated expansions and subsequent delivery at a reduced varying pressure until, at the outlet of the muffler, the pressure is substantially constant, which produces a substantially uniform outward flow with the consequent elimination of all pulsating sound.

The core 2 is provided with three discs 5, 6, and 7. The discs are each provided with

flanges 8 that fit the interior of the shell 1. The discs are secured to the cones 3 and 4. The small ends of the cones extend through the discs 5 and 7 which form the inlet and the outlet of the muffler. The ends of the cones are slotted on opposite sides, as at 10, and a split clamping ring 11 surrounds the slotted portions of the smaller ends of the cones whereby the muffler may be connected in the exhaust pipe of the engine. The pipe may be inserted within the ends of the cone, and the rings 11 may be secured in position to clamp the protruding ends of the cones about portions of the exhaust pipe. If the pipe is smaller than the inlet and outlet formed by the protruding ends of the cones, a connector 12 which have portions of reduced cross-sectional area are inserted within the ends of the cones, and the clamping rings 11 are clamped about portions of the connector 12 having the larger diameter, and the exhaust pipe may be inserted within the protruding portion of the connector. The connectors 12 are also provided with slots 13 located on opposite sides and so that when the exhaust pipe is inserted in position in the connector 12 the protruding portion of the connector may, in each case, be clamped about the exhaust pipe by means of the split clamping ring 14 which is located around the protruding portion of the connector 12. Thus, a tight connection may be made to the portion of the exhaust pipe located intermediate the muffler and the engine and the portion of the exhaust pipe that forms the delivery pipe of the exhaust products from the muffler.

The discs 5 and 7 surround and are welded to the smaller ends of the cones, while the disc 6 is provided with a raised central portion 18, which forms interior and exterior cylindrical surfaces 19 into which and over which the larger ends of the cones 4 and 3, respectively, fit. This affords an exceedingly convenient means for connecting the parts of the core. Preferably, the cones are welded to the disc 6 along the surfaces that contact with the substantially cylindrical surfaces of the disc 6.

A central cylindrical sheet metal pipe 22 fits the interior of the smaller end of the cone 3 and terminates at the disc 6. The disc 6 forms a closed wall within the cone 3. The 5 pipe 22 is provided with a plurality of openings 23 in the vicinity of the disc 6 which opens into the interior of the cone 3 at the larger end of the cone and forms an expansion chamber for the expansion of the gases. 10 The remainder of the pipe 22 is non-perforated, so that the gases are directed to the larger chamber formed by the larger end of the cone 3. Near the smaller end of the cone 3, the cone is provided with a plurality of 15 openings 24. Thus, the gases pass to the portion of the cone having a reduced cross-sectional area and through the openings 24 into the larger chamber 25, formed between the smaller end of the cone 3 and the shell 1, 20 which again forms an expansion chamber, the gases previously having passed through a passageway having a reduced cross-sectional area. The gases then pass through the opening 26 formed exterior to the cone 3 and 25 in the disc 6. The outward flow of the gases is towards the end of the shell that surrounds the smaller end of the cone 4 and the gases expand and recoil from the disc 7. Intermediate the reduced pulsatory movements of 30 the gas through the openings 26, it passes through the openings 27 from the reduced cross-sectional area of the chamber 28 into the larger end of the cone 29. The gases then pass through the smaller end of the 35 cone to the outlet formed by the smaller end of the cone 4 that protrudes from the disc 7 and the shell 1.

In order to prevent rotation of the gases through the outlet, the smaller end of the 40 core 2 is provided with partitions 32 that extend across the cone and, in the particular construction shown, divide the cone from substantially the midpoint of its axis to the outer end of the cone, into four chambers 33, which 45 reduces all rotation of the gases, and enables a steady outward flow of the gases from the interior of the cone 4.

The core 2 comprising the cones 3 and 4 and the discs 5, 6, and 7, and the parts located 50 within the cones, are first assembled, the cones being connected together by the disc 6. The flanges 8 of the discs 5, 6, and 7, being formed to fit the interior of the cylinder 1, the core may be assembled and then pushed 55 into the cylinder 1. This forms an exceedingly convenient means of forming the muffler and reduces the cost of manufacture.

I claim:

1. In a muffler, a cylindrical drum, a core 60 comprising a pair of cones and three discs, two of the discs surrounding the smaller ends of the cones and the third disc located at the larger ends of the cones, the said discs fitting the interior of the drum, a cylindrical tubular member located within one of the cones 65

and extending to the central disc of the muffler and having openings in the vicinity of the central disc, the last named cone having openings near the inlet of the muffler, the central disc having openings exterior to the said cones, the other of the cones having openings near the central disc, the smaller end of the last named cone forming the outlet of the muffler. 70

2. In a muffler, a cylindrical drum, a core comprising a pair of cones and three discs, two of the discs surrounding the smaller ends of the cones and the third disc located at the larger ends of the cones, the said discs fitting 75 the interior of the drum, a cylindrical tubular member located within one of the cones and extending to the central disc of the muffler and having openings in the vicinity of the central disc, the last named cone having openings near the inlet of the muffler, the central disc having openings exterior to the said cones, the other of the cones having openings near the central disc, the last named cone having radially extending partitioning walls 80 extending from the axis of the cone to the inner surface of the cone for dividing the interior of the cone into sector shaped compartments, the smaller end of the last named cone forming the outlet of the muffler. 85

In witness whereof I have hereunto signed my name to this specification.

JOHN J. COMPO.
